R. T. Knight,

Door Spring.

N° 59,414.

Patented Nov. 6, 1868.

UNITED STATES PATENT OFFICE

ROBERT T. KNIGHT, OF PHILADELPHIA, PENNSYLVANIA.

IMPROVED SPRING FOR CLOSING DOORS.

Specification forming part of Letters Patent No. 59,414, dated November 6, 1866.

To all whom it may concern:

Be it known that I, R. T. KNIGHT, of Philadelphia, Pennsylvania, have invented an Improvement in Self-Closing Doors; and I do hereby declare the following to be a full, clear, and exact description of the same, reference being had to the accompanying drawings, and to the letters of reference marked thereon.

My invention consists of a spring contained within a recess formed in the door and attached at one end to the latter and at the opposite end to a stationary pin on which the door turns, all substantially as described hereinafter; also, of a detachable grooved strip secured to the edge of the door and arranged in respect to the spring as hereinafter described, the spring acting as an efficient medium for automatically closing the door, and at the same time being concealed from view.

In order to enable others skilled in the art to make and apply my invention, I will now proceed to describe its construction and operation.

On reference to the accompanying drawings, which form a part of this specification, Figure 1 is a front view of a door-frame and a door, partly in section, with my improvement; Fig. 2, the same as Fig. 1, showing the door in a different position and part of it removed to show the spring; and Fig. 3, a plan view, partly in section.

A represents the floor, and B and B' the two jambs, and C the lintel of a door-frame, within which is hung a door, D. To one edge of the door is secured a detachable strip, D', which is rounded on the outside, as shown in Fig. 3. The inner face of the strip D' and the edge of the door to which the strip is attached are grooved, so as to form a vertical recess or chamber, X, into which project two brackets, a and a', on the edge of the door.

To the floor A is secured a plate, b, a pointed projection, c, on which extends into a recess in a plate, d, secured to the lower edge of the

door D, and through the bracket a and through a plate, f, secured to the upper edge of the door, extends a pin, g, which is prevented from turning by its square end e projecting into a square recess in a plate, i, secured to the under side of the lintel C.

To the lower end of the pin g and to the bracket a' are secured the opposite ends of a spring, h, the latter consisting, in the present instance, of a narrow flat strip of steel, which, when the door is closed, is straight and in a line with the axis of the door. As one end of the spring is secured to the door and the other to the stationary pin g, any change in the position of the door will twist the spring, as shown in Fig. 3, so that when the door is released it will be at once closed by the recoil of the spring. As the spring is contained in the door it cannot be readily tampered with. At the same time, being concealed, it has not the unsightly appearance presented by exposed door-springs. A spring consisting of two or more parallel rods or wires secured to the pin g and to the bracket a' may be substituted for the spring described. Access may be had to the spring after removing the strip D'.

I claim as my invention and desire to secure by Letters Patent—

1. A spring, h, contained within a recess or chamber formed in the door and attached at one end to a projection on the door and at the other to a stationary pin on which the door turns, all substantially as set forth.

2. The detachable grooved strip D', arranged on the edge of the door in respect to the spring as set forth.

In testimony whereof I have signed my name to this specification in the presence of two subscribing witnesses.

ROBERT T. KNIGHT.
